UNITED STATES PATENT OFFICE.

ALBURTIS EAGLE, OF NORTHAMPTON, PENNSYLVANIA.

JOURNAL-BOX AND LUBRICATOR.

SPECIFICATION forming part of Letters Patent No. 365,246, dated June 21, 1887.

Application filed January 5, 1887. Serial No. 223,454. (No model.)

To all whom it may concern.

Be it known that I, ALBURTIS EAGLE, a citizen of the United States, residing at Northampton, in the county of Bucks, State of Pennsylvania, have invented a new and useful Improvement in Journal-Boxes and Lubricators, which improvement is fully set forth in the following specification and accompanying drawings, in which—

10 Figure 1 represents a side elevation of a journal-box and lubricator embodying my invention. Fig. 2 represents a longitudinal vertical section thereof. Fig. 3 represents a view of the interior thereof. Fig. 4 represents a 15 transverse section thereof.

Similar letters of reference indicate corresponding parts in the several figures.

My invention consists of a journal-box and lubricator having certain novel features, as 20 will be hereinafter fully set forth, and claimed.

Referring to the drawings, A represents the journal-box formed of suitable material, and B represents the journal or axle located therein.

C represents a lubricator cup or box, which 25 is formed of suitable material, and located either aside of the box A or above the same, as shown by the dotted lines, Fig. 2.

In the wall D of the box is a duct, E, which leads horizontally from the bottom of the cup 30 C to the bottom of the chamber F of the box, which contains the journal B. The inner sides of the lower portion of said chamber F are beveled or flaring, as at G, whereby said sides are set out from the adjacent sides of the 35 journal B, the outer side walls of the box A furnishing the bearings for the shaft.

When the cup C is on top of the box A, the duct E extends vertically through the wall D, as seen by the dotted lines, Fig. 2, and is then 40 deflected in the direction of the full lines of the duct E to the bottom of the chamber F.

The cup C has a supply-opening, H, which is closed by a cap, J, and likewise an opening in its side, which is covered by a piece of 45 transparent material, forming a window, K, through which the condition of the lubricant in the cup C may be viewed.

It will be seen that the oil or lubricant passes 50 through the duct E, and, reaching the periphery of the journal, is taken up by contact with

the latter and so carried around the chamber F, whereby the journal is thoroughly lubricated. Every particle of lubricant in the cup may be directed into the chamber, so that the lubrication continues, even if the supply is 55 low. Some of the lubricant reaches the sides of the lower portion of the chamber F, and would be taken up by the sides of the journal B directly to the side openings of the box A, and thus caused to escape, were it not for the 60 flaring sides of said lower portion of the chamber, which increase the width of said chamber and permit the oil to return thereto, while the portion of the axle contiguous to the journal is properly lubricated without the lubricant being necessarily forced out through the side openings of the box, which would be occasioned if the sides of the journal B were in close contact with the lower portion of the chamber F. 65

The box and cup are made in sections, each section being preferably cast in one piece of metal.

I am aware that it is not new to form a journal-box having flaring inner sides; neither is 70 it new to provide the same with a lubricator-cup leading into the journal-chamber, nor to provide the cup with a glass covering, whereby the contents thereof may be readily seen, and such I do not claim; but I am not aware that 75 the peculiar construction and arrangement of parts herein set forth, whereby a cheap, serviceable, and efficient device is obtained, are old.

Having thus described my invention, what I 80 claim as new, and desire to secure by Letters Patent, is—

A combined journal-box and lubricator consisting of the journal-box A, with chamber F, the outer side walls of which furnish the bearings for the shaft, the said chamber having beveled inner sides at the lower portion thereof, and the lubricator-cup C, with the duct E, leading to the lowest part of chamber F, said parts being combined and operating substantially as described.

ALBURTIS EAGLE.
